UNITED STATES PATENT OFFICE.

ALLEN B. NORTON, OF CLEVELAND, OHIO, ASSIGNOR TO ALUMINUM COMPANY OF AMERICA, OF PITTSBURGH, PENNSYLVANIA, A CORPORATION OF PENNSYLVANIA.

METAL MOLD AND METHOD OF CASTING.

Application filed February 23, 1924. Serial No. 694,479.

This invention relates to the art of casting metallic articles in permanent molds and in particular to a mold and a method for casting relatively large, thin walled, hollow articles. Although it is especially applicable to aluminum alloys, the principles underlying the construction and operation of the mold and the steps of the method are applicable to various other metals and alloys, notably light metals having melting points within a range of 150 degrees centigrade of pure aluminum, approximately.

One object of the invention is to construct a mold for casting relatively large, thin walled articles having a gate and feeder cavity at one side of the casting cavity and means for bypassing molten metal from the casting cavity adjacent the feeder cavity into more remote parts of the casting cavity. Another object of the invention is to construct a mold for casting relatively large, thin walled articles having a gating cavity or a gating and feeder cavity from either or both of which metal is bypassed through feeders to a portion or portions of the casting remote from the first mentioned gating cavity or gating and feeder cavity, the bypassing consisting of a connecting cavity of greater thickness than the minimum section of the casting.

A further object is to construct a permanent mold for thin walled articles in which one or more passages are provided above the casting cavity and communicating therewith at separate points, the cross sectional dimensions of the passages being greater than the thickness of the adjacent casting walls.

A still further object is to construct a new and improved permanent mold for casting hollow articles of metals having melting points comparable to pure aluminum in which many improved features of construction will appear more in detail and be claimed hereinafter.

Another object is to provide a method of casting in a permanent mold a sound, thin walled, hollow, relatively large article composed of metal having a melting point comparable to pure aluminum.

Another object is to provide a new and improved method of quickly introducing molten metal comparable in melting point and specific gravity to aluminum into an iron mold in a manner to exclude and prevent the entrapping of air in the molten

metal and to prevent agitation or splashing of the metal as it enters the mold, and leading the highly heated metal from the casting cavity adjacent the gate into the somewhat cooler but advancing metal in the casting cavity to complete the filling of the mold.

Another object is to provide a new and improved method of casting thin walled articles composed of metal having a melting point comparable to aluminum in permanent molds which comprises leading molten metal smoothly and rapidly through a single gate into a casting cavity, causing part of the metal to flow toward remote parts of the casting cavity and causing other parts of the metal while still highly heated to reunite with the metal in the remote parts of the casting cavity and to complete the filling of the cavity.

Other objects will appear, and will be pointed out hereinafter.

In the drawings accompanying this specification and forming a part thereof one form of device is shown embodying my invention and adapted to carry out my new and improved process.

Figure 1 is a top plan view of an assembled mold constructed in accordance with my invention.

Figure 2 is a longitudinal view taken on line 2—2 of Figure 1 partly in cross section and showing certain of the mold members in side elevation.

Figure 3 is a vertical cross sectional view taken on line 3—3 of Fig. 1.

Figure 4 is an enlarged fragmentary detail view of certain of the structures shown in Figure 3.

Figures 5 and 6 are respectively enlarged fragmentary cross sectional views taken on lines 5—5 and 6—6 respectively of Figure 3.

Figures 7 and 8 are respectively side elevation and top plan views of an article with the gate metal attached as cast in apparatus embodying my invention and by means of my improved process.

Figures 9, 10, 11, 12, 13, 14, and 15, respectively represent cross sectional views taken on lines 9—9, 10—10, 11—11, 12—12, 13—13, 14—14, and 15—15 of the gate and feeders of Figure 7.

Figures 16 and 17 are respectively fragmentary cross sectional views taken on lines 16—16 and 17—17 of Figure 8, and

Figure 18 is a perspective view of the casting shown in Figures 7 and 8 but with certain of the risers broken away.

Referring more particularly to Figures 1 to 6 inclusive my improved form of mold comprises a base member 1 having at one end thereof a post 2 secured in a vertical hole 3 in base 1 by means of a nut 4. Pivotally mounted on post 2 are two pairs of mold members 5 and 6, the members 5 being seated on the base 1 and adapted to slide thereon into and out of abutting position while mold members 6 are seated on the top of members 5 and adapted to move with or independently of members 5. Handles 7 are provided on members 5 and 6 to facilitate movement of these members about the post 2. A pilot 8 is provided on the upper surface of base 1 to assist in positioning the members 5 with respect to each other and to form the end wall of the casting cavity which in the case illustrated, is formed partly in the top of the base 1. A similar pilot 9 is likewise formed on the top surface of members 5 to assist in positioning members 6.

The meeting faces of mold members 5 and 6 are suitably recessed to form a gate 10, a rise 11 communicating therewith and in turn 30 communicating with a casting cavity 12. If desired, a feeder or riser cavity 13 may be provided in communication with casting cavity 12 and opposite to feeder cavity 11. Means are provided for withdrawing molten metal from the casting cavity 12 near the feeder cavity 11 and returning it to the casting cavity at points remote from the feeder cavity 11. Such cavities are preferably formed in the faces of the mold 35 member 6 above the casting cavity 12 as represented by numeral 14. The connections between these passages and the casting cavity 12 being indicated at points numbered 15. It may be desirable to provide additional riser cavities from these 40 passages 14 as for example those herein designated by 16.

A core 17 comprising a hollow shell seats upon the top surface of member 6 and extends downwardly into the casting cavity to form the inner end and side walls of the casting cavity. This core is preferably composed of two parts. The tubular portion 18 which is adapted to extend into the casting cavity and form the inner end and side walls thereof is secured to a plate-like top 19 as by means of cap screws 20 which screw into bosses 21 of the part 18. The plate 19 is preferably somewhat larger than the tubular part 18 so that it rests upon the top of members 6 thereby supporting the core in the casting cavity. The handle 22 secured to plate 19 of core 17 serves as a means to remove the core from the casting cavity. The tubular portion 18 of the core

17 has its side wall which lies opposite the gate 10 and feeder cavity 11 enlarged somewhat as at 23, so that a portion thereof may be cut away and an insert 24 secured thereto as by cap screws 25. The purpose of providing the insert 24 at this point, is to permit long continued use of the core by periodically renewing the insert if the latter shows any tendency to pitting or deterioration due to contact therewith of the first entering molten metal. This provision for the insert is, however, largely precautionary rather than necessary.

To form a handle receiving bracket on the article to be cast for example, consisting of two independent arms extending outwardly and then toward each other as shown in Figure 8, I have provided two co-operating core pins 26 and 27. Core pin 26 is horizontally located in one of the mold members 5 being seated in a suitable recess therein so that its top lies substantially flush with the top of the mold member. A handle 28 serves to move the core pin back and forth in the mold member 5. The inner end of this core pin is recessed on the top surface thereof as at 29 to conform with the lower end 30 of core pin 27 and receives this portion 30 when the core pins are in assembled position preliminary to making a casting. Core pin 27 comprises an enlarged outer end portion 31 adapted in certain positions of the pin to rest upon the top surface of mold member 6; a shank 32 and an enlarged lower end 30. The configuration of the shank 32 and the end 30 will more clearly appear by reference to Figures 5 and 6 where it will be seen that the shank 32 is offset slightly with respect to the center line of the end portion 30 and where it will appear that the portion 30 has opposite side surfaces 33 inclined converging upward. The purpose of the offsetting of the shank 32 and the inclination of surfaces 33 will be pointed out hereinafter.

I prefer to provide an insert 34 in the side of the tubular part 18 of the core which lies opposite the core pin 27 and may secure such an insert in the position by such means as a screw 35 and dowel pin 36. Although I have previously mentioned recesses 14 as being formed in the inner faces of mold members 6, I find it advisable to form the part of such recesses lying opposite the core pin 27 in the core itself and accordingly has so shown these recesses in Figures 3 and 4 where a portion of recess 14 is formed in the insert 34.

In operating the mold herein described the mold members 5 and 6 are brought into the assembled position shown in Figure 1 and the core is lowered into place in the casting cavity. Core pin 27 is raised to the position shown in Figure 3 and core pin 26 is then inserted therebeneath as also shown

in this figure. After the molten metal has been poured into the gate 10 and has filled and solidified in the casting cavity in the various passages, riser or feeder and gate 5 cavities the core pin 26 is withdrawn to approximately the position shown in Figure 4. Core pin 27 is then pushed downwardly until the end portion 30 thereof clears the handle bracket on the casting or until the 10 outer end portion 31 of the pin seats on the top of mold member 6. The core 17 is then elevated out of the casting cavity and finally the mold members 5 and 6 are swung horizontally about the vertical pivot post 2 15 and the casting is ready to be removed from the mold. The core pin 27 is seated in a suitably shaped recess in mold member 6 and moves therewith when the latter is moved. To remove the core pin 27 from 20 the handle bracket on the casting the shank 32 of the pin has been offset from the vertical center line of the pin an amount sufficient to permit the shank 32 to pass through the space between the separate arms of the handle bracket as the mold member 6 is turned about the pivot post 2. The upwardly converging side surfaces on head 33 of pin 27 can be readily separated from the adjacent casting without injury thereto. The mold 25 is then ready to be reassembled preliminary to the making of another casting.

In Figures 7 to 16 inclusive I have shown a casting which may be made in the mold disclosed in Figures 1 to 6 inclusive, this 30 article embodying certain features of my invention and cast by my new and improved method. In making relatively large thin walled cup-like castings as shown in permanent molds it is often difficult even when the molds are highly heated to cause the 35 metal to flow into all parts of the casting cavity and completely fill the same. This difficulty is perhaps more pronounced with metals having a crystallization shrinkage 40 and melting point comparable to aluminum. Aluminum alloy and other light metals and alloy of melting points comparable to aluminum are particularly difficult to cast into such described wall thicknesses and shapes. 45 Furthermore these metals because of their lightness tend to occlude and retain air and other gases and thus render the castings 50 porous or pitted unless special precautions are observed to prevent the entrapping of 55 air or the entry of any entrapped air into the casting cavity. With the foregoing difficulties in mind, I have provided a gate 10 which is designed to prevent the entry 60 of entrapped air into the casting cavity and at the same time to permit the rapid yet smooth and unagitated filling of the casting cavity with molten metal which gate per se, does not form a part of this particular invention but is described and explained in 65 a co-pending application, now Patent No. 1,553,628 issued September 15, 1925, and is claimed in co-pending application, Serial No. 15,796 filed March 6th, 1925, communicates at its lower end with an enlarged upright feeder cavity 11 adjacent to and in communication with the casting cavity through a short narrow passage extending throughout substantially the entire height of the casting cavity, the function of this feeder cavity being to provide a relatively large supply of highly heated molten metal adjacent to the casting cavity to serve as a reservoir in filling up voids in the casting due to the shrinkage of the metal therein as it cools and thereby to insure complete filling of the cavity and substantially elimination of any cracks or voids due to crystallization shrinkage of the metal in the casting cavity. In relatively large castings such as are herein disclosed, I have found it preferable to employ an enlarged feeder cavity 13 substantially opposite to the gate 10 and feeder cavity 11. This feeder or riser 13 also communicates through a short narrow passage with the casting cavity and acts in substantially the same manner as does the feeder cavity 11. 70 A novel and important feature of my present invention is the provision of means for withdrawing molten metal from the casting cavity near or adjacent to its point of entry from the feeder cavity 11 and gate 10 into the casting cavity and conducting the still highly heated molten metal into parts of the casting cavity remote from the feeder cavity 11 and in leading this still highly heated molten metal into the forward part of the metal advancing in the casting cavity so that the latter metal is restored 75 approximately to its former temperature or so that the temperature of the metal is elevated sufficiently to insure travel of the molten metal to all parts of the casting cavity and complete filling thereof before solidification takes place. Although withdrawing and reintroducing the molten metal just described may be carried out by various means, I have found that it may conveniently be done by means of the passages 14 and 15. In relatively large articles such as 80 are herein disclosed I have found it preferable to employ passages 14 and 15 on opposite sides of the casting cavity as shown in Figure 3. 85 My improved method as practiced on the casting shown herein will be understood by reference to these figures and particularly to Figure 18. The molten metal introduced into the gate passage 10 flows downwardly therethrough into the feeder cavity 11 and thence into the casting cavity 12. As the pouring proceeds rapidly the gate 10 and riser 11 become filled and the metal in the casting cavity flows toward the remote parts 90 thereof and into the feeder or riser 13. 130

Since the side walls of the casting cavity are relatively thin the metal tends to cool quickly and to flow sluggishly thereby causing the casting cavity adjacent to feeder cavity 11 to 5 become filled to its top while the remote parts of casting cavity are being filled. The head of highly heated molten metal in the gate 10 and feeder 11 causes the metal in the casting cavity 12 to rise through the 10 openings or passages 15 adjacent the feeder cavity 11 and flow through passages 14 toward the remote parts of the casting cavity and to flow into the casting cavity through the other openings or passages 15 while still 15 highly heated. The enlarged passages 14 and the risers 16 thereabove have a capacity for a substantial quantity of molten metal and the cooling rate thereof is correspondingly decreased so that the metal which 20 enters the casting cavity is more highly heated than the metal in the thin parts of the casting cavity. The reentry of this highly heated molten metal and a mixture thereof with the advancing portion or forward 25 part of the metal flowing in the casting cavity tends to increase the temperature of the latter or at least to maintain it at the temperature necessary for satisfactory flowing of the metal in the casting cavity 30 and the complete filling thereof. After the casting cavity has been completely filled the risers 16 may and probably do assist in compensating for any crystallization shrinkage occurring in the casting itself.

35 It will thus be seen that by withdrawing highly heated molten metal from the casting cavity near its point of entry there into and then reintroducing such metal while still highly heated into the casting cavity 40 at points remote from the gate, I am able to completely fill the casting cavity for relatively large thin walled castings even though the metal has a relatively high melting point as compared with tin and a relatively high crystallization shrinkage as compared with iron, as an example of both of which I may mention aluminum alloy.

45 For the purpose of further assisting those skilled in the art to practice my invention, I have shown in Figures 7 to 18 inclusive 50 various views and cross sections of the size and shape of cavities which I have found satisfactory in making castings of the class described and in practicing my improved process. For example, Figures 9, 10, 11, 12 and 13 illustrate cross sectional dimensions 55 of the gate: Figures 14 and 15 represent corresponding dimensions of the feeders 11 and 13 and Figures 16 and 17 show the relative size of the casting cavity and passage 14. In Figures 7, 8, 16, 17 and 18, 10^a represents 60 the gate metal of a casting, 11^a the riser metal formed in riser cavity 11, 12^a the casting form in the casting cavity 12, 13^a the metal solidifying in the riser or feeder 13

and 14^a, 15^a and 16^a representing the metal solidifying in the passages 14, 15 and 16 respectively.

It will be noted that the passage 14 which connects each of the portions thereof immediately beneath the risers 16 is somewhat smaller in cross sections than these later portions. Although these passages could be enlarged if desired they are as shown considerably larger in cross sectional dimensions 75 than the adjacent sections of the casting and have been found entirely satisfactory for the desired purpose.

Having thus described my invention, what I desire to secure by Letters Patent is defined and what is claimed it being understood that various changes in the structure herein shown may be made by those skilled in the art without departing from the scope 80 of my invention and further that the steps of my method may be altered, varied or changed somewhat also without departing 85 from the scope of my invention.

What I claim is:

1. The new and improved method of casting a thin walled hollow article composed of a metal having a melting point comparable to that of pure aluminum in a permanent mold which comprises introducing the molten alloy into a suitable casting cavity 90 through a gate at one side thereof, permitting part of the metal to flow in the casting cavity toward the parts thereof remote from the gate, and withdrawing molten metal from adjacent the gate and leading 95 it into the casting cavity at a point remote from the gate.

2. The new and improved method of casting a thin walled, hollow aluminum base 100 alloy article in a permanent mold comprising feeding metal smoothly and rapidly into a suitable casting cavity at one side thereof, permitting part of the metal to flow in the casting cavity toward remote parts thereof, and withdrawing highly heated molten 105 metal from adjacent to the point of entry of such metal into the casting cavity, and adding it to the metal flowing in the casting cavity as the latter metal cools to complete 110 the filling of the mold.

3. The new and improved method of casting thin walled, cup shaped aluminum base 115 alloy articles in a permanent mold comprising feeding molten alloy into the casting cavity at one side thereof, permitting the metal to advance in the casting cavity toward remote parts thereof and maintaining in a highly heated condition the forward 120 part of the advancing metal until the casting cavity is completely filled.

4. The new and improved method of casting relatively large thin walled cup shaped articles composed of aluminum base 125 alloy in a permanent mold comprising leading highly heated molten alloy into one side 130

of a suitable casting cavity, permitting metal to advance in separate streams toward remote parts of the casting cavity and at intervals uniting the forward parts of each 5 of the said separate streams.

5. The new and improved method of casting relatively large thin walled cup shaped articles composed of aluminum base alloy in a permanent mold comprising leading mol- 10 ten alloy into the casting cavity at one side thereof, permitting the alloy to advance toward remote parts of the cavity in separate streams of different cross sectional dimensions and at intervals reuniting the flowing 15 metal of the two streams.

6. The new and improved method of casting relatively large thin walled cup shaped articles composed of aluminum base alloy in a permanent mold comprising introducing 20 molten metal into one side of a casting cavity, permitting the metal to advance toward remote parts of the cavity through separate passages and uniting the advancing metal in the separate passages at intervals.

25 7. The new and improved method of casting relatively large thin walled cup shaped articles composed of aluminum base alloy in a permanent mold comprising introducing molten metal into a casting cavity, permitting the metal to advance toward remote parts of the cavity and maintaining substantially constant the temperature of the forward position of the advancing metal in the casting cavity by adding directly thereto 35 molten metal taken from the casting cavity adjacent to its point of entry thereinto.

8. The new and improved method of casting relatively large thin walled cup shaped articles composed of aluminum base alloy in a permanent mold comprising introducing 40 molten metal into a casting cavity, permitting the metal to advance in the casting cavity toward remote parts thereof, and maintaining the forward part of the advancing metal in fluid condition by adding thereto at spaced points highly heated mol- 45 ten metal withdrawn from the casting cavity adjacent to its point of entry thereinto.

9. A mold for making aluminum alloy 50 castings comprising relatively movable mold members having their adjacent faces suitably recessed to form a casting cavity for an enlarged cup shaped article, a gate cavity and a feeder cavity, the gate and feeder 55 cavities communicating with the casting cavity at one side thereof, a core supported on the mold members and extending into the casting cavity with the inner end and side surfaces spaced apart from the adjacent sur- 60 faces of the mold members to form a thin walled casting, and a recess formed in one of the mold members separate from but communicating with the casting cavity at points adjacent to and remote from the feeder 65 cavity.

10. A mold for making aluminum alloy castings comprising relatively movable mold members having their adjacent faces suitably recessed to form a casting cavity for an enlarged cup shaped article, a gate cavity 70 and a feeder cavity the gate and feeder cavities communicating with the casting cavity at one side thereof, a core supported on the mold members and extending into the casting cavity with the inner end and side surfaces spaced apart from the adjacent surfaces of the mold members to form a thin walled casting, and a recess formed in one of the mold members separate from but communicating with the casting cavity at 75 points adjacent to and remote from the feeder cavity, the cross sectional dimensions of the said recess being greater than those of the casting cavity.

11. A mold for making aluminum alloy 80 castings comprising relatively movable mold members having their adjacent faces suitably recessed to form a casting cavity for an enlarged cup shaped article, a gate cavity and a feeder cavity, the gate and feeder 85 cavities communicating with the casting cavity at one side thereof, a core supported on the mold members and extending into the casting cavity with the inner end and side surfaces spaced apart from the adjacent surfaces of the mold members to form a thin walled casting, and two recesses formed one in each of the mold members separate from but communicating with the casting cavity at points adjacent to and remote 90 from the feeder cavity.

12. A mold for making aluminum alloy 95 castings comprising relatively movable mold members having their adjacent faces suitably recessed to form a casting cavity for an enlarged cup shaped article a gate 105 cavity and a feeder cavity the gate and feeder cavities communicating with the casting cavity at one side thereof, a core supported on the mold members and extending 110 into the casting cavity with the inner end and side surfaces spaced apart from the adjacent surfaces of the mold members to form a thin walled casting, and with recess formed between adjacent surfaces of mold member and core separate from but communicating with the casting cavity at points adjacent to and remote from the feeder cavity.

13. A mold for making aluminum alloy 120 castings comprising relatively movable mold members having their adjacent faces suitably recessed to form a casting cavity for an enlarged cup shaped article, a gate cavity and a feeder cavity, the gate and feeder 125 cavities communicating with the casting cavity at one side thereof, a core supported on the mold members and extending into the casting cavity with the inner end and side surfaces spaced apart from the adjacent surfaces of the mold members to 130

form a thin walled casting, and a recess formed in one of the mold members separate from but communicating with the casting cavity at points adjacent to and remote from the feeder cavity and communicating with an enlarged riser recess.

14. A permanent mold for aluminum castings comprising relatively movable mold members suitably recessed in their abutting faces to form an enlarged casting cavity, and communicating gate and feeder cavities, a core extending into the casting cavity and forming the inner walls of the casting cavity for a thin walled article, and means for withdrawing molten metal from the casting cavity adjacent to the feeder and returning it to the casting cavity at points remote from the feeder.

15. A permanent mold for aluminum castings comprising relatively movable mold members suitably recessed in their abutting faces to form an enlarged casting cavity, and communicating gate and feeder cavities, a core extending into the casting cavity and forming the inner walls of the casting cavity for a thin walled article and means for withdrawing metal from the top of the casting cavity adjacent to the gate and returning it to the top of the cavity remote from the gate.

16. A permanent mold for aluminum castings comprising movable mold members suitably recessed in their abutting faces to form an enlarged casting cavity, and communicating gate and feeder cavities, a core extending into the casting cavity and forming the inner walls of the casting cavity for a thin walled article and means for withdrawing molten metal from the casting cavity adjacent the feeder and returning it to the casting cavity at points remote from the feeder, said means comprising a separate passage formed between a side surface of the core and the adjacent surface of the mold members.

17. A permanent mold for aluminum castings comprising movable mold members suitably recessed in their abutting faces to form an enlarged casting cavity, and communicating gate and feeder cavities, a core extending into the casting cavity and forming the inner

walls of the casting cavity for a thin walled article and means for withdrawing molten metal from the casting cavity adjacent the feeder and returning it to the casting cavity at points remote from the feeder, said means comprising a separate passage formed between a side surface of the core and the adjacent surface of the mold members and riser passages communicating with and located above said passage.

18. A mold having two mold members hinged at one side, casting and gate recesses in abutting faces of mold members, a core to form a thin walled, cup shaped casting cavity, a horizontally movable mold part in one of the mold members, a vertically movable core co-operating with the mold members, core and mold part to form on the casting a handle comprising outwardly extending converging arms having their inner surfaces diverging downwardly, the said movable core comprising an enlarged lower end and a shank of reduced size offset with respect to the vertical center line of the said lower end.

19. The new and improved method of casting thin walled, aluminum base alloy articles in a permanent mold comprising feeding molten alloy into the casting cavity at one side thereof, permitting the metal to advance in the casting cavity toward remote parts thereof and adding, to the forward part of the advancing metal until the casting cavity is completely filled, additional molten metal having a temperature higher than the said advancing metal at the point of junction of the metals.

20. A permanent mold for aluminum castings comprising relatively movable mold members suitably recessed in their abutting faces to form an enlarged casting cavity, and communicating gate and feeder cavities, a core extending into the casting cavity and forming the inner walls of the casting cavity for a thin walled article, and means for withdrawing molten metal from adjacent to the feeder and leading it into the casting cavity at points remote from the feeder.

In testimony whereof I hereunto affix my signature this 18th day of February, 1924.

ALLEN B. NORTON.
